Attorneys.

UNITED STATES PATENT OFFICE

CARL P. BAMMER, OF VENICE, CALIFORNIA

EDGE TRIMMER FOR SHOE SOLES

Application filed January 11, 1928. Serial No. 245,891.

This invention relates to shoe finishing machines, and has for an object the provision of a quick-change plate whereby the trimming knives customarily used on shoe finishing machines may be changed much more expeditiously than heretofore.

Another object is the provision of a quick-change plate as above described, requiring no tools for the placing or removal thereof in the operation of changing the trimming knives.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to the drawings wherein similar reference characters denote similar parts throughout:

Figure 1 is a longitudinal, sectional view of a trimming knife held in position upon its mandrel by one of the improved quick-change plates of my invention.

Figure 2 is a side elevation of the plate of Figure 1.

Figure 3 is a front elevation of the plate of Figure 1.

Figure 4 is a sectional view similar to Figure 1, but showing a modification of my quick-change plate.

Figure 5 is a side elevation of the plate of Figure 4.

Figure 6 is a front elevation of the plate of Figure 4.

Figure 7 is a sectional view similar to Figure 1, but showing another modification of my quick-change plate.

Figure 8 is a front elevation of the plate of Figure 7, a portion thereof being broken away to better reveal the relation of the cutting knife thereto.

All of the embodiments of the improved quick-change plate of my invention shown

in the drawings and described herein are intended for use to removably retain a cutting knife 11, of the type ordinarily used for trimming shoe soles and heels, against a shoulder 12 upon a collar 13 which is slidably mounted upon the mandrel or main shaft 14 of a shoe finishing machine. A spring 16 under tension between a portion of the collar 13 and a collar 17 rigid with the shaft 14 urges the collar 13 and its shoulder 12 toward the end of the shaft; and a plurality of plates 18 integral with the shoulder 12 are adapted to extend between the plates 19 of the knife 11 as clearly shown in Figures 1, 4 and 7.

The parts so far described are purely conventional and no claim is laid to their novelty, but the essential features of my invention are incorporated in the quick-change plate indicated in its entirety at 21.

In the embodiment shown in Figures 1, 2 and 3 the plate 21 comprises a threaded portion 22 for the reception of which the end of the shaft 14 is drilled centrally and threaded as at 23 complementarily to the threaded portion 22. An enlarged head 24 is provided upon the end of the threaded portion 22, the diameter of this head preferably being larger than the diameter of the knife 11 so that a guiding shoulder 26 is provided to assist in properly holding the shoe sole or other article being trimmed against the revolving trimming knife 11. An annular shoulder 27 upon the inner face of the head 24 is adapted to enter the central aperture 28 of the cutting knife 11 to retain the two in concentric alignment; and an annular shoulder 29 on the outer face of the head 24 is provided with knurling 31 to permit the quick-change plate to be positioned and removed without the use of any tools.

While the operation of trimming shoe soles is being carried out it is frequently necessary to change the cutter 11 for one of different dimensions. When my improved quick-change plate is employed for retaining the cutter 11 in position upon its mandrel 14 this substitution of cutters 11 may be carried out with the utmost expedition simply by placing the palm of one hand against the knurled shoulder 29 and turning the plate 21 in the

100

proper direction to remove the threaded portion 22 from the threaded portion 23 of the mandrel. The knife 11 may then be slipped from the end of the shaft and replaced by the substituted knife, after which the plate 21 may again be inserted and tightened against the knife 11 by turning in the opposite direction, the palm of the hand being employed as before to carry out the turning operation. It will be readily appreciated that the employment of a quick-change plate of this nature requiring no tools whatever for its removal or tightening will afford a very appreciable saving in time in the operation of a shoe finishing machine. The operators of such machines are generally working under considerable pressure of time which will make the employment of my quick-change plate especially desirable.

In Figures 4, 5 and 6 a modification of my quick-change plate is shown. The head 36 is provided with a central aperture 37 which is threaded to be received upon the outer end 38 of a screw 39. The inner end 41 of the screw 39 is of smaller diameter than the outer end 38 and is threaded with preferably the conventional threads to make it receivable within the threaded bore 23 of the mandrel 14. When this embodiment is used it is intended that the screw 39 shall be positioned in the bore 23 of the mandrel 14 first, a screw driver slot 42 being provided in the outer end of the screw 39 for this purpose. When the screw 39 has been so positioned the head 36 may readily be attached or detached therefrom in precisely the same way as that employed when operating the embodiment previously described.

In Figures 7 and 8 another modification is shown in which the head 46 is provided with a smaller threaded central aperture 47. A screw 48 having the same size threads throughout its length is intended to be inserted into the threaded aperture 23 of the mandrel 14, after which the head 46 may be expeditiously positioned thereon and removed therefrom in the same manner as that described in connection with the other embodiments.

I claim:

1. In combination with a shoe finishing machine having a revoluble mandrel with a shoulder adjacent one end thereof, a trimming knife upon said end, a quick-change plate bearing against the outer face of said trimming knife, a threaded shank integral with said plate, and a complementarily threaded axial socket in said mandrel whereby said plate may optionally be locked against said knife or displaced therefrom to permit removal of said knife.

2. In combination with a shoe finishing machine having a revoluble mandrel with a shoulder adjacent one end thereof, a trimming knife upon said end, a quick-change plate

bearing against the outer face of said trimming knife, a threaded shank on said plate, and a complementarily threaded socket in said mandrel whereby said plate may optionally be locked against said knife or displaced therefrom to permit removal of said knife. 70

3. In combination with a shoe finishing machine having a revoluble mandrel, a trimming knife removably mounted on said mandrel adjacent an end thereof, a quick-change plate bearing against the outer face of said knife, a headless screw threaded into a complementarily threaded socket in said end of the mandrel and removably retaining the plate in position, said plate being removable from and positionable upon said mandrel by being grasped by the hand of the operator and turned in respect to said mandrel. 75 80

4. In combination with a shoe finishing machine having a revoluble mandrel with a shoulder adjacent one end thereof, a trimming knife having an aperture therethrough to permit placing upon said end, a quick-change plate bearing against the outer face of said trimming knife, an annular shoulder on the inner face of said plate entering the aperture in said knife, a knurled shoulder on the outer face of said plate, a threaded shank carrying said plate, and a complementarily threaded axial socket in said mandrel whereby said plate may optionally be locked against said knife or displaced therefrom to permit removal of said knife. 85 90 95

5. In combination with a shoe finishing machine having a revoluble mandrel with a shoulder adjacent one end thereof, a trimming knife having an aperture therethrough to permit placing upon said end, a quick-change plate of larger diameter than said knife and bearing against the outer face thereof, an annular shoulder on the inner face of said plate entering the aperture in said knife, a threaded shank integral with said plate, and a complementarily threaded socket in said mandrel whereby said plate may optionally be locked against said knife or displaced therefrom to permit removal of said knife. 100 105 110

In testimony whereof I have signed my name to this specification.

CARL P. BAMMER. 115
